DESIGN FOR A BACK FOR BILLFOLD OR SIMILAR ARTICLE

Sidney Hack, Jamaica Estates, Long Island, N. Y.

Application December 29, 1944, Serial No. 117,148

Term of patent 7 years

(Cl. D87—3)

To all whom it may concern:

Be it known that I, Sidney Hack, a citizen of the United States, residing at Jamaica Estates, Long Island, in the county of Queens and State of New York, have invented a new, original, and ornamental Design for a Back for Billfold or Similar Article, of which the following is a full, clear and exact description, reference being had to the accompanying drawing, forming a part thereof.

In the drawing:

Fig. 1 is a front perspective view of a back for billfold or similar article showing my new design; and

Fig. 2 is a rear perspective view of the same.
I claim:

The ornamental design for a back for billfold or similar article, as shown.

SIDNEY HACK.
